UNITED STATES PATENT OFFICE

JACQUES S. FRAZIN, OF YONKERS, NEW YORK

DESIGN FOR A SERVING TRAY

Application filed May 10, 1933. Serial No. 48,061. Term of patent 3½ years.

To all whom it may concern:

Be it known that I, JACQUES S. FRAZIN, a citizen of the United States, residing in Yonkers, in the county of Westchester, State of New York, have invented a new, original, and ornamental Design for a Serving Tray, of which the following is the specification, reference being had to the accompanying drawing, forming part thereof.

In the drawing, Fig. 1 is a top plan view, and Fig. 2 is a side elevation of the serving tray showing my new design.

I claim:

The ornamental design for a serving tray, as shown.

JACQUES S. FRAZIN.
